UNITED STATES PATENT OFFICE.

MORTIMER G. MERRITT, OF SPRINGFIELD, MASSACHUSETTS, ASSIGNOR TO
THE MERRITT MANUFACTURING COMPANY, OF SAME PLACE.

TYPE-WRITING MACHINE.

SPECIFICATION forming part of Letters Patent No. 510,984, dated December 19, 1893.

Application filed January 9, 1893. Serial No. 457,789. (No model.)

To all whom it may concern:

Be it known that I, MORTIMER G. MERRITT, a citizen of the United States, residing at Springfield, in the county of Hampden and State of Massachusetts, have invented new and useful Improvements in Type-Writing Machines, of which the following is a specification.

This invention pertains to improvements in the class of type-writing machines in which the platen-roll is mounted on a carriage which has a movement, in the direction of the platen axis, past the common impact point for the characters on the key-operated type-bars, and in conjunction with which carriage is an escapement mechanism having connection with each of the key-levers and also the space-bar for imparting the intermittent letter-space movement to the platen and its carriage. In this class of machines a device is usually employed for such a throw-out action of the escapement devices relative to the platen-carriage, that, at will, the carriage may be run endwise any desired distance within the limits of its movement.

This invention particularly pertains to an improved form or construction of the throw-out or shift device for the escapement mechanism, and consists, to this end, in the construction and combination of parts all substantially as will hereinafter fully appear and be set forth in the claims.

Reference is to be had to the accompanying drawings in which this improved device is shown in its application upon a type-writing machine.

Figure 1 is a plan view of the greater portion of the machine including the improved escapement shift. Fig. 2 is a vertical, cross-sectional view of parts of the machine comprising, and adjacent to, the escapement and its shift, as taken on line 2—2, Fig. 1, the improved device being shown in its normal position, while Fig. 3 is substantially a similar view showing the shift device moved in its position for effecting the shift of the escapement. Fig. 4 is a perspective view of the shift-device, detached from the machine, but indicated as in its operative relation to a part of the escapement.

In the drawings, A represents various parts of the frame of the typewriting machine, the illustration here given being of the well known Densmore machine, and B B represent the main, and auxiliary parts of the carriage for the platen roller, C, said carriage being mounted for its longitudinal run on the front and rear horizontal support rails D, D. The platen carriage has a frame or appliance, G, at its rear which is engaged so as to move in unison therewith, the same being to all intents and purposes, so far as this invention is concerned, to be regarded as a part of the carriage; and it has secured at an under portion thereof a horizontal and longitudinally ranging-bar, H, the rear edge of which is ratcheted, as indicated at a. A form of escapement device is here shown for the usual co-operative action with the said ratcheted-bar which is of substantially the construction illustrated in Letters Patent of the United States granted to George S. Heath under date of May 17, 1892, No. 475,057. Other forms of escapement may, however, be substituted for this one but the one illustrated is practical and efficient and the improved device which forms the subject matter of this invention is well adapted for co-operation therewith.

It will be briefly mentioned that the escapement device comprises the carrying-arm, b, which is pivotally mounted on the bracket, c, for a swinging reciprocatory movement in a vertical plane. This arm, b, has an annularly or hook-formed pawl-member, b², and a longitudinally-sliding and spring-pressed pawl, d, which is movable reciprocatingly and longitudinally on the arm, b, and is, with said arm, bodily movable vertically and transversely in the reciprocatory movements of the arm. Each time a key is depressed and permitted to return to its normal position, the arm, b, is vertically rocked carrying the part, b², out of engagement with the ratcheted bar and bringing the pawl, d, into position to engage the next tooth, thus permitting the carriage and the supplemental portion, G, and the bar, H, to be moved endwise by the usual spring drum the distance of one of the ratchet-teeth to letter-space. The said bracket, c,

has a foot-lug which is mounted on a vertical pivot, c^2 , so that the aforementioned pawl-devices, b , b^2 , and d , may be swung bodily rearward away from engagement with the ratcheted-bar, the torsion spring indicated at c^3 , serving to maintain the pawl-devices of the escapement normally in engagement with the ratcheted bar. All of these escapement devices which have thus been, in detail, referred to, as well as their operation, are fully set forth in the aforesaid Letters Patent to which reference may be had, if found desirable, to a more full understanding of this description of escapement.

Now, proceeding to describe the improved escapement shift device the same will be seen, by reference to the drawings, to consist of a light strip or bar, J , which is pivotally mounted on the part, G , of the carriage, the same being extended longitudinally in a line which is slightly above the ratchet-bar and an intermediate portion of this bar, J , which is adjacent the inner working extremity of one of the aforesaid pawls, is adapted to be swung thereagainst to force the pawl-devices rearwardly as the latter are readily permitted by the manner of their pivotal support on the part, c^2 . The said bar, J , is extended longitudinally at one end slightly beyond the corresponding end of the carriage, B , where it is provided with the forwardly and angularly extended arm, f , which, in its forward extension, has enough of elevation above the rear-support rail, D , to permit its depression without interference by said rail or the lug of the machine frame on which the said rail is supported; on the other hand this arm has a comparatively compact arrangement relative to said support-rail, D , and the end of the carriage, and the carriage rotating knob, g , so as not to be an inconvenience to, or be unfavorably affected by, said parts in the usual operations or manipulations, respectively thereof.

As will be perceived, especially on reference to Fig. 4, the entire shift device is of a most simple, light, and inexpensive construction, and also, as incidental thereto amply durable. Setting forth the precise construction in detail of this device, as shown, it consists of the light-bar, J , two light, perforated ear-pieces, h, h^2 , having suitable angular lugs, h^3 , whereby to rivet to the said bar, J , and the arm, f , which also has the angle-lug, h^3 , whereby it is also riveted to the bar, J .

Having thus described my invention, what I claim, and desire to secure by Letters Patent, is—

1. In a typewriting machine, in combination, the carriage having the horizontal ratcheted-bar, H , the bracket mounted for a rearward swinging movement, and a pawl-ended arm mounted on the bracket for a vertical swinging movement, and a pawl having a longitudinally reciprocating movement on the said arm, the bar, J , pivoted to the carriage for a rearward and forward swinging movement against and from said pawl device, and the forwardly extended arm, f , for swinging the said bar, substantially as and for the purposes set forth.

2. In a typewriting machine, in combination, a rear part or appliance for the carriage having the ratcheted-bar, H , the bracket mounted for a rearward swinging movement, and a pawl-ended arm mounted on the bracket for a vertical swinging movement, and a pawl having a longitudinally reciprocating movement on the said arm, the bar, J , with the ear-pieces, h, h^2 , pivoted to the aforesaid part of the carriage, and the arm, f , with the lug h^3 , whereby it is riveted to said bar, J , substantially as and for the purposes set forth.

MORTIMER G. MERRITT.
